UNITED STATES PATENT OFFICE

STEWART L. CAMPBELL, OF BERKELEY, CALIFORNIA, ASSIGNOR TO JOHN GRANT, OF LOS ANGELES, CALIFORNIA

ROTARY UNDERREAMER

Application filed December 3, 1927. Serial No. 237,358.

This invention relates to rotary underreamers or expansive reamers designed particularly for rotary drilling, and the present invention is somewhat of the same nature as 5 that set forth in my prior application Serial No. 85,126, filed February 1, 1926, now Patent No. 1,667,190, dated April 24, 1928, entitled Rotary underreamer, both these inventions involving reamers which utilize a 10 cutter or cutters swinging about eccentric vertical axes. The present invention involves certain improvements having more particularly to do with the mounting of the cutters, the means whereby swinging movement its obtained, and the manner of assembling and 15 disassembling the reamer.

In the following specification I explain in the specific detail preferred and illustrative embodiments of the present invention, reference for this purpose being had to the accompanying drawings, in which:

Fig. 1 is a side elevation of an underreamer in accordance with the present invention;

Fig. 2 is a central longitudinal section of the same, with parts shown in elevation for clarity of illustration;

Figs. 3 and 4 are cross-sections on the respective lines 3—3 and 4—4 of Fig. 2, but showing the cutters expanded, whereas Figs.

30 1 and 2 show them contracted;

Fig. 5 is a section on line 5—5 of Fig. 1, showing the cutters contracted inside a well casing;

Fig. 6 is a section on line 6—6 of Fig. 1, 35 showing the cutters contracted inside a well casing;

Fig. 7 is a similar section showing the cutters expanded;

Fig. 8 is an elevation, with parts broken 40 away in section, of the interior parts of the reamer, showing the reamer in partial state of disassembly;

Fig. 9 is an end view of the parts shown in Fig. 8;

Fig. 10 is a cross section on line 10—10 of Fig. 2;

Figs. 11 and 12 are detail views showing varying forms of cutters which may be used in the reamer;

50 Fig. 13 is a view similar to portions of

Fig. 2, but showing a modified construction; Fig. 14 is a cross-section on line 14—14 of Fig. 13; and

Fig. 15 is a diagrammatic section illustrating the movement of a cutter and its manner 55 of casing engagement.

Fig. 16 are plan, side and front elevations of the cutter, the contour lines 40a to 40d having their curvature exaggerated to more clearly illustrate that these contour lines do not 60 have the same center.

In the drawings I show a reamer with a body made up of an interior body core 10 and an exterior tubular shell 11 which fits over the interior body core and is secured 65 thereto at its upper end. The shell may be rotatively secured to the core by means of spaced lugs 13 which enter corresponding recesses 14 in the body core; and such means as bolts or cap screws 13a may be used to 70 prevent relative longitudinal movement between the core and the shell. In some of the broader aspects of the invention the core and shell may be regarded as forming a single 75 piece body; and this is true so far as all functional operations of the reamer are concerned. It is as regards convenience of assembly and disassembly that the body is made of two parts.

The body core has, below the lower end 80 of shell 11, a recessed or reduced portion 15 around which the swinging cutters 16 are arranged, the cutters swinging inwardly into the recessed space below the lower end of shell 11, when they are in collapsed position, and swinging outwardly to project their outer ends or edges beyond the periphery of shell 11 when expanded. Below the reduced portion 15 the body has an enlargement 56 which is formed to afford a bearing block 90 for the lower ends of the cutter stems and is also formed, as hereinafter described, to allow of ready removal of the cutters from the body. Below the enlargement 56 the body has the usual screw-threaded pin 17 for connection with a drill bit 18, the water courses 19 of the drill bit being fed through a longitudinal water course 20 which extends through the whole length of the body. The body at its upper end is provided with the 100

usual screw-thread pin 21, for connection with a rotary drill stem.

Any suitable number of cutters may be used. In the particular illustration here I prefer to show four, these cutters being preferably equally spaced around the central axis of the tool. The body core thus is provided with four equally spaced longitudinal bores 23 which take, and preferably form bearings for, the cutter stems 24. In the specific form here shown I prefer to show the cutters mounted on their stems so that the stems and cutters rotate together. This provides a convenient arrangement whereby torsion springs 25 may be applied directly to the stems for the purpose of swinging the cutters. Thus, the cutter stems 24 extend up through the bores 23 into and preferably completely across recesses 25, these recesses being sunk in from the exterior surface of the body core and being normally covered by the shell 11.

A coiled torsion spring 26 is applied to each cutter stem within a recess 25, the torsion spring surrounding the cutter stem, having one end anchored at 26a to the cutter stem and the other end connected at 26b to the body. Any suitable arrangements for anchoring the ends of the spring may be utilized; as shown in Fig. 2, one end of the 30 spring may simply be set in a hole or recess in the body and, as shown in Fig. 10, the other end of the spring may simply be entered into a hole in the stem. When the parts are assembled these springs are tensed so that 35 they will tend at all times, with proper force, to swing the cutters to their expanded positions—the positions shown in Figs. 3, 4 and 7; and the cutters must be moved to the contracted positions of Figs. 5 and 6 against the 40 tensions of the springs.

The cutter 16 may be of any desired character, and may have a formation-cutting edge of any desired type. In most of the figures of the drawings I show cutters 16 in the simple 45 form of blades having a formation shearing edge 16a, or an inset blade 16f (see Fig. 1) which presents a downwardly facing cutting edge at the lower horizontal edge of member 16; but, as shown in Figs. 11 and 12, the 50 cutter members 16 may carry other types of cutting elements, such as a rotatable toothed roller 16b. In Fig. 11 the blade 16 is shown recessed at 16c to take rollers 16b, while in Fig. 12 the blade is shown as if it were entirely cut through, leaving only what may be regarded as the crank arms 16d, which carry the roller supporting pin or trunnion 16b. Here the parts 16d and 16e form the rigid 55 part of the swinging cutter, and may be regarded as a swinging cutter carrier to carry roller 16b. Likewise, in Fig. 11, blade 16 may be regarded as a cutter carrier, which carries ultimate cutting element 16b; and similarly in the other figures the blades 16 60 may be regarded as cutter carriers or cutter

elements which carry the ultimate cutting elements, being in that case the cutting or shearing edge 16a or blade 16f.

Regardless of how the ultimate cutting element may be formed or provided, cutter elements 16 are, as before described, mounted to be swung on their stems 24 between the expanded and collapsed positions shown in the several views. In their expanded positions the outer cutting elements of members 16 project beyond the periphery of shell 11, and the cutters 16 back up against stop shoulders 30 which are formed on the body, and, in this specific design here illustrated, are formed on the lower edge of body shell 11. 70 The cutter stems 24 rotate on axes eccentric of the central axis of the whole tool; and it will be noted that the stop shoulders 30 are located so as to limit swinging movement of the cutters to such positions that they are, 75 in their expanded positions, non-radial to the central axis of the tool. In its expanded position, no part of the cutters can reach a position where the line drawn through the central axis of the body, and through the 80 swinging axis of the cutter, will pass through any part of the cutter which lies outside the body of the tool, and which is therefore engaged, or liable to be engaged, by the lower 85 end of the casing when the cutters are collapsed.

The upper outer corner of each cutter 16 is beveled off, as shown at 40, over its entire edge surface. In the drawing this beveling is shown as curved in elevation outline, but that is immaterial, as the beveling may be of any desired configuration in elevation. Whatever such elevation configuration may be, the beveled face is preferably made of such 90 form as to present a surface for engaging 95 with the bottom of the casing or the casing shoe, rather than a mere line. This characteristic of the beveling is illustrated in Figs. 6 and 7.

Fig. 6 is a horizontal section showing the 100 cutters collapsed inside the casing, the section being taken through the upper parts of the cutters at about the level at which they are struck by the casing. Fig. 7, a section at the same level on the cutters, shows the cutters 110 expanded and the dotted line at C indicates the inside line of the casing. The inside lower edge of the casing or casing shoe will thus strike the cutters along the contour line 40a of the bevel 40; and, as shown in Fig. 7, this 115 contour line near the upper ends of the cutters, is, when the cutters are expanded, substantially concentric with the central axis of the tool and therefore also with the casing. Consequently, the lower edge of the casing 120 will engage the cutters, not on a sharp edge, but along a somewhat extended contour line; and this line of engagement may preferably, 125 as shown in the drawings, extend clear across the whole beveled edge of the cutter. As the 130

tool is moved up through the casing, the cutters are swung in toward the position of Fig. 6. The contour line 40a is thus of course thrown out of concentricity with the tool center, but the lower parts of beveled surface 40 are shaped so that, as the casing edge moves relatively downwardly on the cutters and the cutters are swung in, the cutters still present a contour line of engagement to the casing edge. Thus, when the cutters are in fully collapsed position, with their outer edge faces resting against the interior of the casing, their contour lines illustrated at 40d (the lowermost contour lines of the beveled faces) are substantially concentric with the tool axis and with the casing. Where a shearing edge cutter of the type shown in Fig. 6 is used, it may be advisable to make this lowermost contour line, and the outer peripheral edge face of the cutter, not quite exactly concentric with the casing, in order to remove the vertical shearing edge 16a just slightly from the interior casing face, or to take off the pressure of that edge on the casing just enough to keep that edge from cutting into the casing when the tool is being moved through the casing. Thus the center of the lowermost contour line 40d, with the cutters collapsed, may be at such a point as is indicated at C¹ in Fig. 6. Such special contouring of the beveled casing engaging surface toward its lower end does not materially change the fact that the edge face of the cutter engages the casing interior preferably on a rather broad face of engagement, rather than on a single vertical line of engagement. And, in any case, it will be seen that the cutter never engages the casing at a sharp edge only, always engaging the casing at least in a medial portion of the beveled face 40, and preferably engaging the casing, as far as is practical, across substantially the whole of that beveled face. What I have said of the contours illustrated by the lines 40a and 40d is also true of the intervening horizontal contours 40b and 40c of the beveled face.

To explain more completely the configuration and action of the upper bevelled cutter faces, Figs. 15 and 16 are referred to. The plan view of Fig. 16 exaggerates the curvature of the arcuate contour lines 40a—40d to clearly show that these arcs do not have the same center but do have equal radii. These figures show diagrammatically the motion of one cutter with reference to the casing or pipe, being in the nature of a horizontal section through the cutter at the level at which, expanded, it strikes the lower inner edge of the pipe or shoe. Thus the full line showing in Fig. 15 shows the cutter just as it is shown, expanded, in Fig. 7; and the contour line 40a is shown, as in Fig. 7, as a contour line in the cylindric inner surface of the pipe, indicated by the circular line C.

Now, as the cutter swings in toward collapsed position it successively takes the positions shown in dotted lines, Fig. 15, indicated 50a—50d. It of course takes an infinite number of such positions, but four will suffice for illustration and description. The cutter reaches these intermediate positions by being pulled up into the casing; so a horizontal section at the lower edge of the pipe (that is what Fig. 15 is) will show successive contours 40a—40d on the bevelled cutter corner at the said level having as centers a, b, c and d respectively. And each of these successive contours are, as the cutter swings inwardly by reason of pipe contact, also in the cylindric inner surface C of the pipe, and therefore, in the then position of the cutter, concentric with the pipe center and the axis of the reamer.

Thus, for "position 50a" the contour 40a is shown to coincide with the pipe surface; and for "position 50b" the contour 40b. For entirely collapsed position, the contour 40d has been explained. It will accordingly now be understood that the bevel at the cutter corner is of such shape or curvature that, illustrated by contours, it has, in any one of its successive swinging positions, a contour in the horizontal plane of the lower end of the pipe, which contour is located substantially in the inner cylindric surface of the pipe. In other words, the cutter has a bevelled surface that can be described and located by horizontal plane contours that, as the cutter swings inwardly, are successively concentric with the pipe center and located in a circle or cylinder corresponding in diameter with the inner surface of the pipe or shoe. These several contours are not all, at any one time or cutter position, so concentric; only one is so concentric for any one cutter position. That fact is illustrated by the concentric position of contour 40a in the full line showing in Fig. 15, and by the dotted line showings of contours 40b and 40d on the full line showing of the cutter in Fig. 15. Only contour 40a is concentric in that full line position; and contours 40b, 40c and 40d do not become concentric until the cutter has swung inwardly to the corresponding positions. But, the successive contours, of which only a few are shown in Fig. 15, becoming thus successively concentric as the cutter swings in, it will now be seen how the cutter presents to the pipe, at all times and in all positions, a line of contact extending horizontally across its pipe contacting edge or surface, rather than a mere point of contact; the pipe contacting surface of the cutter being made up of, or defined by, a series of just such lines.

Where rollers are used, as in Figs. 11 and 12, they preferably project somewhat beyond the outer edge surface of member 16; but the upper ends of the rollers are tapered as at

40f to form substantial continuations of the bevels 40 and so that the casing may continue to have the same collapsing action on the rollers as it has had on the bevel surface 5 40 as the tool is moved up into the casing.

From what has been said it will now be readily understood how the cutters are thrown from their expanded to their contracted positions by engaging with the casing; the fact that the cutters are limited in all their projecting parts to non-radial positions, and the fact that the cutters engage the casing on a broad beveled face, insuring easy collapsing action without any liability of 10 the cutters digging into the casing and binding. In their positions as collapsed by casing engagement, the cutters are somewhat in the position shown in Figs. 5 and 6; but they may move somewhat further inwardly until they 15 are collapsed entirely within the circle of the body. In order to accommodate this further collapsing movement, and at the same time to allow the cutters at their pivoted edges to bear inwardly against the reduced portion 15, 20 when expanded, the inner faces of the cutters may be somewhat recessed as is indicated at 50. This slight recessing allows the cutters to move to their collapsed positions and still have their rounded pivoted edges in engagement 25 with the reduced part 15; and the reduced part, particularly when the cutters are expanded, acts as an abutment to take stresses directly from the cutters to the body without putting undue strains upon the cutter stems. 30 For instance, in Fig. 4, the direction of rotation of the tool is left-handed (Fig. 4 being a bottom view). The cutting stress exerted on the outer cutting edge of the cutter 16 is therefore in the direction indicated by the arrow 35 applied to the uppermost cutter, as shown in Fig. 4. Such stress induces a stress of the cutter against the stop shoulder 30 in the direction indicated by the arrow applied at that shoulder; with the result that a pressure 40 stress is developed at the pivotal edge of the cutter against the reduced part 15 in the direction indicated by the arrow applied at that point in Fig. 4. Consequently, the direct bearing of the pivoted edge of the cutter 45 against the part 15 takes substantially all pressure and shearing stress off the cutter stem 24, relieving that stem of any liability to be bent or sheared.

In the particular form and design here shown each cutter has a lower extension stem 24a which extends down below the cutter and into enlargement block 56. In one form of device this enlargement block is integral with the body and is provided with bearing notches 55 of the configuration best shown in Figs. 8 and 9. Each notch has a substantially semi-cylindric rear bearing surface 55a and a flaring side wall 55b, the angle which this side wall makes with the plane determined 50 by the center of the tool and the center of the

corresponding cutter being less than the angle made with that plane by the corresponding stop shoulder 30; so that the cutter, in its position stopped by shoulder 30, has not swung outwardly far enough to clear the flaring side wall 55b. This relationship of parts is indicated most clearly in Fig. 7.

In the normal assembled position, the lower ends of stems 24a rest upon the upper end surface of drill bit 18, and by removing the drill bit, and after shell 11 and springs 26 have been removed, the cutters may be moved downwardly far enough to disengage them from shoulders 30, the normal clearance between the lower edges of cutters 16 and the upper face of block 56 being greater than the vertical dimension of shoulders 30. Consequently, a cutter 16 may be moved down below shoulders 30 and then may be turned a little further outwardly to such a position as shown in Fig. 9, and then the cutter and its stem may be slipped directly downwardly and out through the notch 55. This operation is indicated in Figs. 8 and 9. The lower corner of the notch wall may be beveled off, as indicated at 55c, to facilitate registration of cutter 16 with the notch when assembling the tool.

On the other hand, a modified construction may be utilized wherein the enlargement 56a 95 may be made removable from the core 10, as is illustrated in Figs. 13 and 14. Block 56a is then removable downwardly from the body after the drill bit 18 has been removed; and then the cutters are removable directly downwardly after shell 11 and spring 26 have been disengaged. In this case it is only necessary that the block 56a have vertical bores to take the stems 24a, as is indicated in Figs. 13 and 14, and it is unnecessary that there be clearance between the lower edges of the cutters and the upper face of the bearing block. To prevent rotation of the bearing block on the body they may be splined together in any suitable manner, such as by the formation indicated at 60 in Fig. 14.

I claim:

1. In an expansive tool of the character described, the combination of a body adapted to be passed through a well pipe, a horizontally swinging cutter element mounted on a vertical axis eccentric of the body axis and adapted to swing outwardly to a position where its outer part is projected beyond the body and beyond the interior diameter of the well pipe through which the tool has passed, means limiting movement of the cutter element to a position where its projecting part is non-radial to the body axis, and the upper corner of the projected cutter part being beveled to a surface having, in a cylindric surface of a diameter substantially equal to the inner diameter of said well pipe, horizontal contours which are successively, in downward progression as 120

the cutter swings inwardly, substantially concentric with the body axis.

2. In an expansive tool of the character described, the combination of a body adapted to be passed through a well pipe, a horizontally swinging cutter element mounted on a vertical axis eccentric of the body axis and adapted to swing outwardly to a position where its outer part is projected beyond the body and beyond the interior diameter of the well pipe through which the tool has passed, means limiting movement of the cutter element to a position where its projecting part is non-radial to the body axis, and the upper corner of the projecting cutter part being beveled to a surface that presents continuously a horizontal line of contact to a casing edge as the cutter is moved up into, and is swung inwardly by, such casing.

20 3. In an expansive tool of the character described, the combination of a body adapted to be passed through a well pipe, a horizontally swinging cutter element mounted on a vertical axis eccentric of the body axis and adapted to swing outwardly to a position where its outer part is projected beyond the body and beyond the interior diameter of the well pipe through which the tool has passed, means limiting movement of the cutter element to a position where its projecting part is non-radial to the body axis, and the upper corner of the projecting cutter part being beveled to a surface that presents continuously a surface portion between its edges to a casing edge as the cutter is moved up into, and is swung inwardly by, such casing, thereby to prevent edges of the cutter from digging into the casing.

4. In an expansive tool of the character described, the combination of a body adapted to be passed through a well pipe, a horizontally swinging cutter element mounted on a vertical axis eccentric of the body axis and adapted to swing outwardly to a position where its outer part is projected beyond the body and beyond the interior diameter of the well pipe through which the tool has passed, means limiting movement of the cutter element to a position where its projecting part is non-radial to the body axis, and the upper corner of the projecting cutter part being beveled to a surface having, in a cylindric surface of a diameter substantially equal to the inner diameter of said well pipe, horizontal contours which are successively, in downward progression as the cutter swings inwardly, substantially concentric with the body axis; and a roller cutter mounted on the swinging cutter element and having an upper tapered part which forms a substantial continuation of the bevel on the cutter element.

5. In an expansive tool of the character described, the combination of a body adapted to be passed through a well pipe, a horizontally swinging cutter element mounted on a

vertical axis eccentric of the body axis and adapted to swing outwardly to a position where its outer part is projected beyond the body and beyond the interior diameter of the well pipe through which the tool has passed, 70 means limiting movement of the cutter element to a position where its projecting part is non-radial to the body axis, the upper corner of the projecting cutter part being beveled to a surface that presents continuously a 75 horizontal line of contact to a casing edge as the cutter is moved up into, and is swung inwardly by, such casing; and a roller cutter mounted on the swinging cutter element and having an upper tapered part which forms a 80 substantial continuation of the bevel on the cutter element.

6. In an expansive tool of the character described, the combination of a body adapted to be passed through a well pipe, a horizontally swinging cutter element mounted on a vertical axis eccentric of the body axis and adapted to swing outwardly to a position where its outer part is projected beyond the body and beyond the interior diameter of the well pipe 85 through which the tool has passed, means limiting movement of the cutter element to a position where its projecting part is non-radial to the body axis, the upper corner of the projecting cutter part being beveled to a surface that presents continuously a surface portion 90 between its edges to a casing edge as the cutter is moved up into, and is swung inwardly by, such casing, thereby to prevent edges of the cutter from digging into the casing; and a 100 roller cutter mounted on the swinging cutter element and having an upper tapered part which forms a substantial continuation of the bevel on the cutter element.

In witness that I claim the foregoing I have, 105 hereunto subscribed my name this 26th day of Nov., 1927.
